UNITED STATES PATENT OFFICE.

VICTOR MAUCK, OF NORRISTOWN, PENNSYLVANIA.

CAN-FORMING MECHANISM.

Application filed August 23, 1921. Serial No. 494,598.

The mechanism and process herein described, are of the general character disclosed in my application Serial #461,274, filed April 14, 1921, for Letters Patent of the United States, but adapt'd for more accurate and rapid production.

My invention is designed and adapted for the formation of cans used in the transportation and storage of ice cream. Such cans are used by wholesalers to deliver ice cream, water ice, frozen custards, etc., to retailers, and are used by the latter to hold such products while they are being dispensed; the emptied cans being thereafter returned to the wholesalers to be refilled and again distributed. Consequently, such cans must be extremely durable to withstand the rough handling, stresses and wear to which they are inevitably subjected. Moreover, as such cans are retained in salt ice water to preserve their contents, their bodies must be permanently liquid tight, and, to prevent contamination of their contents, they must be adapted to be substantially hermetically sealed by closures which can be instantly opened and shut, to facilitate dispensation of their contents. Furthermore, as it is customary to dispense ice cream and similar products by means of substantially hemispherical measuring scoops; such cans must be so designed that substantially all of their contents may be readily removed by such scoops.

Therefore, the object and effect of my invention is to provide cans having the characteristics above contemplated. However, it is to be understood that I do not desire to limit my invention to such specific use.

My invention includes the various novel features of construction, arrangement and procedure hereinafter specified.

In the drawings; Fig. I is a perspective view of a can embodying my invention and provided with a removable lid closure.

Fig. II is a vertical sectional view of the can and closure shown in Fig. I, showing the substantially sealed relation thereof.

Fig. III is a perspective view of a sheet metal cylinder which is the blank from which the body of the can shown in Figs. I and II is formed.

Fig. IV is a perspective view of a cylindrical ring of sheet metal which is the blank adapted to form the flange to support and seal said lid closure on the can body.

Fig. V is an elevation of the ring shown

in Fig. IV, but partly expanded toward its final flanged form.

Fig. VI is an elevation of the partly formed can body with the completed flanged ring fitted upon the top thereof; the bottom of said body being flared to receive the bottom plate.

Fig. VII is a diametrical sectional view of a bottom plate adapted to be fitted in the flared end of the can body shown in Fig. VI.

Fig. VIII is a diagrammatic axial sectional view of said can body, flanged ring and bottom plate; showing said bottom plate supported upon its spinning mandrel, and the opposite end of said body supported upon its expanding and supporting mandrel.

Fig. IX is a fragmentary axial sectional view of said can body and bottom plate, similar to Fig. VIII, but showing the rim of the bottom plate partly spun over the bottom of the can.

Fig. X is a fragmentary sectional view of substantially full size, showing the joint between the can body and the bottom plate as it exists in a finished can.

Fig. XI is a plan view of a spinning lathe and its appurtenances embodying my improvement in can forming mechanism and including hydraulically operative means for completing the formation upon the can of the flange ring shown in Fig. V.

Fig. XII is a front elevation of said spinning lathe shown in Fig. XI.

Referring to Figs. I to X inclusive, which show a convenient form of ice cream can constructed in accordance with my invention; the can body 1 having the removable lid closure 2, conveniently provided with the rigid handle 3, is formed of primarily flat sheet metal. A rectangular piece of such metal, conveniently low carbon steel, is first bent to the cylindrical blank form 5 indicated in Fig. III and then united at its abutting edges 6, conveniently by an electric welding operation, to form a blank from which the body of a can such as shown in Figs. I and II is formed. A cylindrical ring 8 of sheet metal, shown in Fig. IV, is similarly bent and united at its abutting edges 9 to constitute a blank from which may be formed the flange ring 10, as a fixture upon said can body 1, as indicated in Fig. II, to support said lid closure 2 and substantially hermetically seal the joint between the

10

bottom edge of said closure and the can, when in the position shown in Fig. II. Said flange ring blank is expanded, by a pressing operation, from the cylindrical form shown in Fig. IV to the form shown in Fig. V; then pushed upon said cylindrical can blank 5 until its upper edge is flush with the top of the latter. Thereupon, the expanded skirt 11 of said ring blank 10 is pressed inwardly, against said blank 5 until it is curled to form the toric bead 12 indicated in Figs. I, II, VI and VIII. That pressing operation constricts said ring bead 12 upon said can blank 5. However, I subsequently expand said can blank 5 within said flange ring 10, slightly stretching the metal of both of said parts, to insure that they shall thereafter remain in intimate contact. Such expansion is conveniently effected by thrusting the mandrel 13 into said blank 5, as indicated in Fig. VIII.

However, during the aforesaid operation of forming said bead 12 upon said can body 5; I find it convenient to expand the bottom edge of said blank 5 as indicated at 14 in Fig. VI, so that said blank will readily fit over the bottom plate 15 as shown in Fig. VIII.

Said bottom plate 15 is also formed from primarily flat sheet metal, by pressing operations which first cut a circular disk of such metal and then distort it to the cylindrical form shown in Fig. VII. It is to be particularly noted that the circumferential edge 16 of the cylindrical portion 17 of said bottom plate 15, which is presented upwardly in the can against the inner face of the cylindrical wall of the latter, as shown in Figs. VIII, IX and X, is substantially sharp so that there is no crevice formed at the junction of said blanks 5 and 15. The flared lower edge 14 of said blank 5 is then constricted upon said cylindrical portion 17 of the bottom plate, as shown in Fig. VIII. Thereafter, the primarily plane annular flange 18 of said bottom plate 15 is bent over the adjacent edge of said can body blank 5, first, as indicated in full lines in Fig. IX, and, finally, to the form shown in Fig. X wherein said annular flange 18 of the bottom plate 15 is cylindrical and in contact with the outer surface of the cylindrical wall of the can body 1; the cylindrical portion 17 of said bottom plate being likewise in contact with the inner surface of said cylindrical wall of the can body 1. As hereinafter described, I find it convenient to thus distort said bottom plate flange 18 while spinning it upon the mandrel 19 held under pressure in opposition to said mandrel 13; while said mandrels 13 and 19 are rotated in coaxial relation.

Finally, said can body 1 is coated, all over, with a film of some material capable of resisting the corrosive effect of water upon the

ferric metal parts of the can above described. For instance, I find it convenient to coat the can with such a film 20 of block tin, as indicated in Fig. X, so that the entire surfaces of said can 1 and its closure 2 are smoothly continuous and, consequently, may be readily cleaned by washing them.

My copending application aforesaid includes claims for various combinations of the mechanism above contemplated and the process whereby the top of the can blank 5 and its ring 10 are expanded, and the bottom of the can constricted upon its bottom plate 15 and the flange 18 of the latter constricted upon said can body as above described. Although there are various other novel features of procedure in the construction of the can above described; the claims in this case are limited to the mechanism and process whereby said ring 10 is compressed and slightly swaged upon the can, and the latter dislodged from its mandrel.

Said mechanism is shown in Figs. XI and XII wherein 21 is the base frame supporting the stationary head stock 22 having bearings 23 and 24 for the spindle 25 which carries at its inner end said mandrel 19 above described with reference to Fig. VIII and carries the gear wheel 26, whereby said spindle may be rotated. I find it convenient to drive said gear 26 by engagement with the gear 27 on the counter shaft 29 which is mounted in the bearings 30 and 31 on the pedestal 32. Said shaft 29 carries at its outer end the axially movable clutch collar 34 which is keyed to slide upon said shaft 29 and may be operated by the hand lever 35 to engage and disengage the crown clutch members 38 on the hub of the gear 39 which is mounted to loosely rotate on said shaft 29 when said clutch collar 34 is disconnected therefrom. Said gear 39 engages the driving gear 40 on the armature shaft 41 of the electric motor 42; so that said motor may drive said lathe spindle 25 when said clutch mechanism is engaged.

Said base frame 21, supports the tail stock 45 which may be adjusted thereon by means of the crank 46 which is at the outer end of the shaft 47 which carries the gear wheel 48 in engagement with the rack 49 on said tail stock. However, for the purpose herein contemplated, said tail stock 45 is held in stationary position upon said base frame 21, conveniently by two opposite bolts 50, one of which is shown in Fig. XII.

Said tail-stock 45 has the bearings 51 and 52 for the thrust plunger 53 which carries at its front end the idle spindle 55 upon which said mandrel 13, above described with reference to Fig. VIII, is rotatable. As indicated in Fig. XIII; said thrust plunger 53 extends through the stuffing box 56 into the chamber 57 in the casing 58 and may be thrust forward under pres-

- sure of water or other motor fluid admitted to said chamber 57. Said casing 58 has, in axial alinement with said chamber 57, a second chamber, 60, which is slightly smaller in diameter than said chamber 57 and in which the retracting plunger 61 is mounted to reciprocate through the stuffing box 62. Said retracting plunger 61 is provided with a cross head 64 which, as best shown in Fig. XI, is connected by the tension rods 65 with the cross head 67 which is adjustably connected with said thrust plunger 53, conveniently by means of the set screw 68 which engages a screw thread in said yoke.
- 10 The arrangement above described is such that said thrust plunger 53 and retracting plunger 61 are yoked together so that when said plunger 53 is thrust forward, it carries with it said plunger 61, and when said plunger 61 is retracted, it retracts said thrust plunger 53. Such reciprocatory movement of said plungers is conveniently effected by two three-way valves suitably connected with the pipes 70 and 71 which are respectively in communication with said chambers 57 and 60 as indicated in Fig. XII. It is to be understood, that the arrangement is such that the motor fluid may be alternately admitted and exhausted through said pipes 70 and 71, to shift said mandrel 13 toward and away from said mandrel 19.
- 15 Said base frame 21 has the bracket 73 carrying the longitudinal slide bed 74 upon which the longitudinal slide 75 is mounted to be reciprocated by the screw 76 having the hand wheel 77. Said longitudinal slide 75 carries the cross slide 79 which may be shifted transversely to the axis which is common to said lathe spindles 25 and 55, by the screw 80 provided with the hand wheel 81. Said cross slide 79 carries the bearing block 83 provided with the stud shaft 84 on which the spinning roller 85 is mounted to rotate idly.
- 20 It is to be understood that the construction and arrangement of said slides is such that said spinning roller 85 may be shifted toward and away from the common axis of rotation of said mandrels 13 and 19 and also shifted in either direction of the length of said mandrel 19. By manipulating both of said hand wheels 77 and 81 simultaneously, a compound adjustment of the position of said spinning roller 85 may be effected. That is to say, said roller 85 may be simultaneously thrust toward said mandrel 19 and shifted endwise with respect to the latter.
- 25 Said base frame 21 also has the bracket 87 carrying the casing 88, which is similar to the casing 58 aforesaid in that it is arranged to actuate the thrust plunger 89 and the retracting plunger 91 which are coupled by the tension rods 93 extending from the cross head 94, carried by said thrust plunger 89, to the yoke 95 carried by said retracting plunger 91. Said plungers 89 and 91 are mounted to reciprocate in separate chambers in said casing 88, like the plungers 53 and 61 above described with reference to Fig. XII; so that when said plunger 89 is thrust forward, it carries with it said plunger 91, and when said plunger 91 is retracted, it retracts said thrust plunger 89. Said cross head 94 carries the spinning roller 97 which is mounted to rotate idly therein and the arrangement is such that said roller 97 may be moved back and forth, transversely to the axis of rotation of said spinning mandrels 13 and 19 to compress and slightly swage said ring 10 upon the can. However, to facilitate the operation of shifting said spinning roller 97 toward and away from said ring 10, I prefer to provide said casing 88 with the pipe 98 through which a fluid, for instance such as compressed water, is constantly supplied to said chamber in which said plunger 91 is mounted to reciprocate in said casing 88 with a tendency to retract said plunger 91, and carry said spinning roller 97 away from the can; adjustment of said roller toward the can being effected by fluid pressure applied through the pipe 100. That is to say, when the pressure in the pipe 100 leading to the chamber in which said plunger 89 is mounted to reciprocate is greater than the pressure in the pipe 98, said plunger 89 is thrust toward the can, to press the spinning roller 97 against said ring 10, but, when said pressure in the pipe 100 is diminished, it may be counter balanced, or overbalanced, by the constant pressure in the pipe 98 so that the position of said spinning roller 97 and the pressure under which it is maintained in a given position may be directly determined by the operator having control of said pipe 100; conveniently by means of an ordinary two-way valve leading from a supply of pressure fluid and to an exhaust outlet.
- 30 The mechanism above described may be operated as follows: Said mandrel 19 being stationary; a can bottom plate 15 may be fitted thereon, as indicated in Fig. VIII. Said mandrel 13 being retracted, from the position shown in the drawings, toward the right; a can body blank 5, having its bottom edge flared as indicated at 14 in Fig. VI, may be manually fitted upon said bottom plate 15 on said mandrel 19 far enough to engage the latter, about one-half of the length of the cylindrical portion 17 of said can bottom 15, and the opposite end of said can body 5 be held in axial alinement with said mandrel 13. Thereupon, motor fluid is admitted through said pipe 70 to said chamber 57 of the thrust plunger 53, to thrust the latter forward to the position shown in the drawings, thereby thrusting said mandrel 13 into said can body 5 and expanding the

latter into tight engagement with its flange ring 10, as shown in Fig. VIII, and simultaneously thrusting said can body 5 to full extent upon said cylindrical portion 17 of the can bottom 15 as shown in Fig. VIII. However, the flared bottom edge of said body 5 then occupies the position shown in dotted lines in Fig. VIII.

Thereupon, said can should be rotated to spin the bottom flange 18 over the outside thereof as above described. However, if the high pressure necessary to force the mandrel 13 and can blank 5 to the position shown in Fig. VIII be allowed to remain upon said plunger 53, the friction incident to such rotation would be very great. Therefore, in order to relieve the rotary parts of unnecessary friction and yet maintain said mandrels 13 and 19 in the relative position shown in Fig. VIII, to prevent accidental displacement of the can body during the operation of spinning said flange 18; the operator also admits fluid under pressure through the pipe 71, against the retracting plunger 60 to partly counter balance the pressure upon said thrust plunger 53, with the result that pressure of the motor fluid then effective to hold the parts in the relative position shown in Fig. VIII is merely that incident to the difference in diameter between said thrust plunger 53 and said retracting plunger 60 and merely sufficient to prevent displacement of the can body 5 during the spinning operation. Thereupon, the operator shifts the clutch lever 35 to the right in Fig. XI so that the normally loose gear 39 is rigidly connected with the counter shaft 29 to positively turn the spindle 25 and mandrel 19 in the direction of the arrow marked thereon in Fig. XI and thus positively turn the can blank 5 with said mandrel 13, the latter being wedged therein, as above described. Then, while said parts are thus being rotated, an operator manipulates said hand wheels 77 and 81 so as to present the spinning roller 84 against the flared edge 14 of the can blank 5 so as to press the same inwardly to cylindrical form and in contact with the cylindrical portion 17 of said bottom plate 15, as indicated in Fig. VIII. Thereafter, the operator manipulates said wheels 77 and 81 so as to cause said spinning roller 84 to bend said flange 18, of the bottom plate 15, from the plane shown in dotted lines in Fig. IX, to the inclined position shown in full lines in Fig. IX, and proceeds to spin said flange 18 to the cylindrical form shown in Fig. X, in contact with the outer surface of said blank 5, thus completing the bottom spinning operation.

Contemporaneously with the bottom spinning operation aforesaid, another operator admits pressure through the pipe 100 to thrust said spinning roller 97 against the

flange ring 10 to compress and swage the latter into the precise relation with the can which is desired. It is the purpose and effect of the latter spinning operation to not only insure that the edge of said ring 10 toward the bottom of the can shall be brought into intimate contact with the side of the can but also to swage the metal of said ring to form a slight fillet at that edge so that the can may be more readily cleaned than if a crevice or an abrupt angle were formed at the junction of that bottom edge of the ring 10 with the can body.

Thereupon, in order to release the can, thus completed, from its engagement with the mandrels 13 and 19, as shown in Fig. VIII, the operator opens the pipe 70 to exhaust, whereupon, the fluid pressure remaining upon the retracting plunger 61 retracts the latter, with said thrust plunger 53, to withdraw said mandrel 13 from the can 1 and permit the latter to be manually removed from said mandrel 19. However, I find it convenient to facilitate such removal by providing said mandrel 13 with a series of push rods 102, which, when said spindle 55 is thus retracted by the thrust plunger 53 encounter the plate 103 which abuts against said bearing 51, so that said rods 102 push against the top edge of the can 1, where it is reinforced by the ring 10 and dislodge the can from said mandrel 13. Thereafter, the can 1 thus completed may be coated with a composition adapted to resist corrosion and be provided with a lid 2 as above contemplated.

It may be observed that the mechanism shown in Figs. XI and XII has the capacity for operation both as a press and as a spinning lathe. However, I do not desire to limit myself to the particular method of operation thereof above described, as, of course, it may be otherwise used. Moreover, modifications may be made in the various details of construction and arrangement of the mechanism, without departing from the essential features of my invention as defined in the appended claims.

I claim:—

1. The combination with a base frame; of a head-stock mounted on said frame; a spindle journaled in said head-stock; means arranged to rotate said spindle, including a clutch mechanism; a mandrel on said spindle adapted to hold a can bottom plate; a tail-stock on said base frame; a thrust plunger mounted to reciprocate in said tail-stock, in axial alignment with said spindle; a mandrel mounted to rotate at the inner end of said thrust plunger and arranged to engage the top of a can; a circumferential series of push rods carried with the last-named mandrel and arranged to automatically dislodge a can from said mandrel when the latter is retracted; means arranged to recipro-

cate said thrust plunger; a conical spinning roller mounted to rotate on an axis parallel with the common axis of said mandrels; means supported by said base frame, arranged to shift said roller, transversely to its axis, toward and away from said mandrel axis, and axially longitudinally with respect thereto, whereby the rim of said bottom plate may be spun over the bottom edge of said can; another spinning roller mounted to rotate on an axis parallel with the common axis of said mandrels, having its perimeter adapted to swage a flange ring on said can; and means, supported by said base frame, arranged to shift the last named roller, toward and away from said mandrel axis, including a thrust plunger, a retracting plunger and tension rods connecting said plungers for simultaneous reciprocation; said plungers being adapted to be actuated by fluid pressure.

5 10 15 20 25 30 35 40 45

2. The combination with a base frame; of a head stock mounted on said frame; a spindle journaled in said head stock; means arranged to rotate said spindle; a mandrel on said spindle adapted to hold a can bottom plate; a tail stock on said base frame; a thrust plunger mounted to reciprocate in said tail stock, in axial alinement with said spindle; a mandrel mounted to rotate at the inner end of said thrust plunger and arranged to engage the top of the can; means arranged to reciprocate said thrust plunger; a spinning roller, mounted to rotate on an axis parallel with the common axis of said mandrels; means supported by said base frame, arranged to shift said roller, transversely to its axis, toward and away from said mandrel axis, and axially longitudinally with respect thereto; whereby the rim of said bottom plate may be spun over the bottom edge of said can; another spinning roller mounted to rotate on an axis parallel with the common axis of said mandrels; having its perimeter adapted to swage a flange ring on said can; and means, supported by said base frame, arranged to shift the last named roller, toward and away from said mandrel axis, including a thrust plunger, a retracting plunger and tension rods connecting said plungers for simultaneous reciprocation; said plungers being adapted to be actuated by fluid pressure.

5 10 15 20 25 30 35 40 45

3. The combination with a base frame; of a head stock mounted on said frame; a spindle journaled in said head stock; means arranged to rotate said spindle; a mandrel on said spindle adapted to hold a can bottom plate; a tail stock on said base frame; a thrust plunger mounted to reciprocate in said tail stock, in axial alinement with said spindle; a mandrel mounted to rotate at the inner end of said thrust plunger and arranged to engage the top of the can; means arranged to reciprocate said thrust plunger; a spinning roller, mounted to rotate on an axis parallel with the common axis of said mandrels; having its perimeter adapted to swage a flange ring on said can; and means, supported by said base frame, arranged to shift the last named roller, toward and away from said mandrel axis, including a thrust plunger, a retracting plunger and tension rods connecting said plungers for simultaneous reciprocation; said plungers being adapted to be actuated by fluid pressure.

5 10 15 20 25 30 35 40 45

In testimony whereof, I have hereunto signed my name at Los Angeles, California, this thirteenth day of August, 1921.

VICTOR MAUCK.
